UNITED STATES PATENT OFFICE

WILLIAM J. DUNLAP, OF LONG BEACH, CALIFORNIA

SAND AND GAS SEPARATOR

Application filed April 22, 1931. Serial No. 532,034.

This invention relates to improvements in sand and gas separators and may be regarded as an improvement over the construction disclosed in my prior Patent No. 1,759,004, issued May 20, 1930.

An object of the present invention is to provide an improved sand and gas separator for use in oil wells and the like which is of simple construction and which permits of the omission of the so called "mosquito bill" which is attached to and extends downwardly from the standing valve.

Another object of the present invention is to provide a sand and gas separator which will effectively separate sand and most of the gas from the oil and which has a replaceable fitting serving to "bean" back the well so that oil in the well will not be caused to surge by the pump to such an extent as to bring about a caving in of the well walls. In other words the purpose is to choke back to a certain extent the flow of oil to the pump so that the flow of oil from the well into the pump will be more steady or constant, thus reducing the surging tendency and the tendency to bring about cave-ins.

Another object of the invention is to provide a gas and sand separator employing merely two tubes, enabling the device to be constructed in very small sizes and yet effectively separate sand and gas from the oil. The improved construction has the tubes provided with removable closures adjacent the bottom so that the separator can be emptied without being inverted.

With the foregoing and other objects in view, which will be made manifest in the following detailed description, and specifically pointed out in the appended claims, reference is had to the accompanying drawing for an illustrative embodiment of the invention, wherein:

Fig. 1 is a vertical section through the improved sand and gas separator.

Fig. 2 is a horizontal section taken upon the line 2—2 upon Figure 1.

Fig. 3 is a horizontal section taken upon the line 3—3 upon Figure 1.

Fig. 4 is a partial sectional view illustrating a replaceable fitting which may be

employed to "bean" or choke back the well.

Referring to the accompanying drawing, wherein similar reference characters designate similar parts throughout, 10 designates a seat for a standing valve which is conventionally employed in deep well pumps. Connected to the seat 10 are various fittings 11 and a collar 12 which is preferably provided with set screws 13 to prevent unscrewing while in the well. The sand and gas separator comprises an outer tube 14, the upper end of which is screwed into the collar 12. This tube is of considerable length and has a removable closure 15 at its bottom. Within the outer tube there is an inner tube 16 having a removable closure 17 at its bottom. The outer tube 14 is made up of sections and a joint indicated at 18 is preferably arranged near the lower end of the inner tube 16 so that by breaking the joint in the outer tube access to closure 17 may easily be had. A closure ring 19 is welded to the outer tube 14 and to the inner tube 16 adjacent the top thereof, forming a closure between the tubes. A diametrical partition 20 is likewise welded between the tubes and extends from the closure ring 19 to substantially the bottom of the inner tube 16, dividing the interior of the outer tube 14 about the inner tube 16 into two semi-cylindrical chambers 21 and 22. An inlet 23 is formed in the outer tube 14 adjacent its top so as to be arranged on one side of the partition 20. An inlet 24 is formed in the top of the inner tube 16 on the opposite side from inlet 23 so as to be arranged on the opposite side of the baffle.

The distance from closure 17 to closure 15 constitutes a settling chamber 25 for sand and this chamber is located a sufficient distance below the standing valve so that the pump under the most ideal working conditions is incapable of lifting sand from the bottom of this chamber. The interior of closure ring 19 is internally threaded as indicated at 26 and is adapted to receive a standard flow nipple 27 having an aperture or orifice 28 therein of predetermined size, or if desired a flow "bean" 29 having a smaller sized aperture 30 may be substituted therefor.

The operation and advantages of the improved sand and gas separator are as follows. The oil carrying the gas and sand may enter the outer tube through inlet 23. It flows downwardly through semi-cylindrical chamber 22 and during this down flow much of the gas may separate out and escape through the inlet 23. The partition 20 causes the down flow to continue to a point near the bottom of inner tube 16. After passing the bottom of inner tube 16 and the bottom of partition 20, the oil enters the settling chamber 25. In this chamber there is but a slow flow of oil giving the sand, which may be carried by the oil, adequate opportunity to settle out and drop to the bottom of the settling chamber. The oil then flows upwardly through semi-cylindrical chamber 21 and enters the inner tube 16 through inlet 24. Within the inner tube 16 the sand is given a second opportunity to settle out with the sand collecting on top of closure 17. The oil then may flow up through the fitting 27 to the pump. By virtue of the fact that the fitting 27 forms a somewhat constricted passage it has the effect of choking back to a certain extent the supply of oil to the pump. In other words if a conventional deep well pump is employed, on the up stroke of the plunger there is a surge of oil into the pump barrel. If all passages leading to the pump are large and free, this causes a surge of oil to take place in the well which is of a considerable velocity and which is quite sudden. This sudden surge has the effect of bringing about cave-ins in the walls of the well. By having the flow nipple 27 present, as the velocity of the oil to the pump has a tendency to increase, the resistance offered by the aperture 28 likewise increases. Consequently the surging action which would otherwise have a tendency to take place is greatly reduced, eliminating to a large extent the tendency to cave or wash away the walls of the well. If in a given well it is found that the flow nipple 27 is too large to reduce this surging tendency, a flow "bean" 29 may be substituted therefor, having a smaller orifice which will bring about the desired results. This flow "bean" can be easily substituted by detaching the separator from collar 12 which makes the top of the fitting readily accessible for the application of a suitable wrench.

From the above described construction it will be appreciated that the improved gas and sand separator is advantageous in that it employs only two tubes, enabling the device to be made in very small sizes if necessary. It is possible to eliminate the use of the "mosquito bill" and at the same time to "bean" back the well so that surging of the liquid in the well is reduced, if not eliminated. Whenever the separator becomes filled with sand, closure 15 can be removed to empty the outer tube and by breaking the

outer tube at joint 18 closure 17 can be removed to empty the inner tube. In this manner the separator can be emptied while in an upright position.

Various changes may be made in the details of construction without departing from the spirit or scope of the invention as defined by the appended claims.

I claim:

1. A sand and gas separator comprising an outer tube, an inner tube disposed therein, means providing a partition connecting the outer tube to the inner tube, means forming a closure between the top of the outer tube and the inner tube, there being an inlet to the outer tube adjacent its top arranged on one side of the partition, there being an inlet to the inner tube adjacent its top arranged on the opposite side of the partition, and a replaceable member removably mounted at the top of the inner tube having an orifice therethrough of a predetermined size, said replaceable member being relatively short as compared with the length of the inner tube so as to leave the major portion of the interior of the inner tube unobstructed.

2. A sand and gas separator comprising an outer tube, an inner tube disposed therein, means providing a partition connecting the outer tube to the inner tube, means forming a closure between the top of the outer tube and the inner tube, there being an inlet to the outer tube adjacent its top arranged on one side of the partition, there being an inlet to the inner tube adjacent its top arranged on the opposite side of the partition, a replaceable member removably mounted at the top of the inner tube having an orifice therethrough of a predetermined size, said replaceable member being relatively short as compared with the length of the inner tube so as to leave the major portion of the interior of the inner tube unobstructed, and removable closures at the lower ends of said tube, the lower end of the outer tube being disposed a material distance below the lower end of the inner tube to provide an adequate settling chamber for sand, there being a joint in the outer tube adjacent the lower end of the inner tube.

3. A sand and gas separator comprising an outer tube, an inner tube disposed therein, means providing a partition connecting the outer tube to the inner tube, means forming a closure between the top of the outer tube and the inner tube, there being an inlet in the outer tube adjacent its top arranged on one side of the partition, there being an inlet to the inner tube adjacent its top arranged on the opposite side of the partition, and a member having an orifice therethrough of a predetermined size threadedly mounted at the juncture between said closure and the top of the inner tube, said member being

relatively short as compared with the length of the inner tube so as to leave the major portion of the interior of the inner tube unobstructed.

5 In testimony whereof I have signed my name to this specification.

WILLIAM J. DUNLAP.
